COPYING DEVICE

DISCLOSURE OF THE INVENTION

Background

This invention relates, generally, to a duplicating device and particularly to a device for use with cutting saws for duplicating the shape and design of a cylindrically shaped wood turning.

Heretofore, the duplication of intricately designed cylindrically shaped wood turnings as may be found on legs of tables, chairs, bedstands, etc., required the services of a highly trained and skilled craftsman. The cost for such services was usually high, as considerable time and care had to be expended to provide an exact duplication. Attempts to shorten the working time generally resulted in poor quality reproductions.

Objects

Accordingly, it is an object of this invention to provide a device for use with cutting saws capable of duplicating intricately designed wood turnings in a minimum of time but with extremely high duplicating accuracy.

Another object is to provide a device which can be manufactured simply and economically for the home workshop.

Other objects, as well as advantages, of this invention will be apparent from the description to follow and from the accompanying drawings, wherein like numerals refer to like parts and in which:

Drawings

FIG. 1 is a top perspective view showing the device of this invention mounted to a table of a circular saw.

FIG. 2 is transverse sectional of FIG. 1 along line 2-2.

FIG. 3 is a top plan view of FIG. 1.

Description

Referring to the various views, and particularly to FIGS. 1 and 3, the device of this invention is shown comprising, generally, a first support member 18 having a pattern holding means 17, said member 18 being mountable to a table 23 of a circular cutting saw assembly 8, a guide means 16 extending longitudinally across the front and lowermost portion of support member 18, a second support member 29 carrying a tracing means 2 which is capable of moving horizontally and pivotally on guide means 16, and a rotatable wood holding means mounted to the second support member 29.

More specifically, first support member 18 comprises two upstanding side walls 4 and 6 spaced apart by two horizontal, vertically spaced parallel bars 9 and 10 mounted to the lower rear section of side walls 4 and 6. Mounted to bottom bar 9 are at least two metal strips 12 which extend forwardly for stationary attachment to the top of table 23 of circular saw assembly 8 by screws or bolts 20. Extending upwardly and forwardly from top bar 10 are two arms 22 and 24. The forward ends of arms 22 and 24 have a pair of spindle blocks 26 and 28 mounted inwardly to face each other for holding a wood turning pattern 27 therebetween. The other two ends of arms 22 and 24 are attached to slideable sleeves 34 and 36 surrounding top bar 10. This slideable feature allows the distance between spindle blocks 26 and 28 to be varied and thereby accommodate wood turning patterns of different lengths. When the desired distance between the two spindle blocks has been obtained and the wood-turning pattern positioned firmly in place between the spindle blocks, the sleeves are locked in position to prevent movement by tightening locking screws 30 and 32.

Extending longitudinally across support member 18 and in front of side walls 4 and 6 is a guide means 16 for guiding the movement of wheels 13 and 15. To permit wheels 13 and 15 to move horizontally along the tracks' horizontal axes and also to pivot forwardly and backwardly about the tracks' vertical axes

(as shown by the arrows and dotted lines of FIG. 1), the guide means or track 16 preferably has a rounded top 19 and the wheels have a concave riding or contact surface. The guide means 16 can be held in position by mounting the bottom of the guide means to the upper face of metal strips 12 by weld, buried screws or similar means (not shown).

The second support member 29 comprises generally a substantially rectangular frame 40 having two short side bars 42 and 44 and a relatively long forward bar 46 and rear bar 48. Mounted to and extending downward from each end of rear bars 48 of the rectangular frame 40 are spaced forklike extensions 51 and 52 to which are journaled wheels 13 and 15.

When the device of this invention is mounted to a saw assembly by metal strips 12, the rectangular frame 40 lies above and in a plane substantially horizontal to the saw's table top. This permits forward bar 46 to be positioned directly over the rotatable circular saw 50 protruding above the surface of table 23 through slot 53. Extending downward from the forward bar

are two arms 54 and 56, to which centres 58 and 60 are mounted near their lower ends in opposing relationship. In order that a wood piece held by the centres can be rotated, centre 60 is connected to a shaft 62 which is journaled in arm 56. Shaft 62, in turn, is connected to a pulley 64. The pulley is driven by motor 66 mounted on plate 65 attached to rear bar 48 by belt 67. The upper end of arms 54 and 56 are adapted with sleeves 68 and 70 which slidably fit around forward bar 46. Tightening screws 72 and 74 are provided for holding sleeves firmly in place when the desired distance between the centres is obtained and when pulley 64 is aligned to receive belt 67.

With the above arrangement, centres 58 and 60 can both hold and rotate a piece of wood, plastic, metal or like material for duplication. By utilizing a moving saw blade and preferably a rotating circular saw in combination with the contrarotating centres, the material held by the centres is cut cleanly and smoothly. In many instances, very little additional finishing is required to obtain completely finished duplication.

The tracing means referred to generally by numeral 2 is mounted to the back side of rear bar 48 as shown in FIGS. 1 and 2. The finger copying mechanism comprises a vertical member 78 and a base member 80. Each of the aforementioned members has short side walls 82 extending rearwardly and upwardly respectively. The vertical member 78 and base member 80 are pivotably joined by pin 81 through their respective side walls to form an L configuration with the L's short leg providing the vertical member. The pivotal arrangement of members 78 and 80 permits the vertical member to move forward or backward about pin 81 which, in turn, causes second support member 29 to be raised or lowered by a responding pivotal action of wheels 13 and 15 about track or guide means 16. The pivotal movement of the second support member 29 causes wood piece 71 (FIG. 3) held between rotatable centres 58 and 60 to be likewise lowered or raised over cutting saw 50, thus varying the depth of the cut made by cutting saw 50.

The unattached end of base member 80 has a rotatable roller 84 attached thereto and extending outward beyond the edge of the base member 80 where it is loosely contained between spaced parallel bars 9 and 10 of first support member 18. Mounted centrally to vertical member 78 are a pair of vertically spaced ribs 86 and 88. The bottom ends of ribs 86 and 88 extend outwardly and slightly downwardly from the front wall where they are joined to form a single rib extension 90 which extends upwardly and rearwardly at substantially right angles to the downwardly extending ribs 86 and 88. The single rib extension 90 will be referred to from time to time as the tracing finger and is of sufficient length to physically contact a pattern design held between spindle blocks 26 and 28.

Pivotedly mounted between the uppermost portion of the two vertically spaced ribs 86 and 88 is rod 89 which extends rearwardly from pivotal connection 87.

A pair of uprights 76 and 92 extend upward from base member 80 to pivotally hold therebetween a closed cylindrical

sleeve 55. The forward end of sleeve 55 has an opening 93 through which rod 89 enters. The other end of the sleeve is fitted with a rotatable threaded cap 94 to receive the other end of rod 89 which is correspondingly threaded. By rotating cap 94, rod 89 may be drawn forward or pushed backward which, in turn, moves vertical member 78 to which rod 89 is pivotally mounted. As previously mentioned, movement of vertical member 78 elevates or lowers rotating centres 58 and 80 attached to arms 59 and 56 of second support member 29.

Since the design patterns held by spindle blocks 26 and 28 will be of various thicknesses, as well as lengths, the depth of cut required for duplicating the pattern will also vary. This adjustment in cut depth can be controlled by rotating cap 94. To facilitate rotation of cap 94, a tension spring 95 is mounted to intermediate tracing finger 90 and upright 92.

With the structure just described, second support member 29 is capable of moving simultaneously both horizontally and pivotally on track 16.

The weight of the duplicating device is distributed such that the front portion of the device (that portion forward to track 16) is slightly heavier than the rear section. This creates a continuous force downward toward cutting saw 50. However, this downward force, and thus the downward movement of rectangular frame 40, is limited initially by upper horizontal bar 10 which is exerting a counteracting force on roller 84 attached to base member 80. This positions and holds the second support member in the general desired vicinity above cutting saw 50.

Although horizontal movement of tracing means 2 along track 16 can be achieved by manual action, movement can be more controlled remotely by crank 91. Crank 91 is connected to axle 96 rotatably mounted on the outside of side wall 4. An opening 97 in side wall 4 permits a guy wire 98 to pass therethrough. One end of the wire is attached to base member 80. The other end of the wire extends to the other side wall and passes through opening 99, where it is wound about a rotatable axle 77 mounted outside of side wall 6. The wire is returned through opening 99, where it is attached to base member 80. The guy wire 98 is maintained taut by tension spring 100 intermediately positioned in wire 98.

OPERATION

In operation, a pattern or a wood turning 27 (FIG. 3) is placed in between spindle blocks 26 and 28 and locked in place by turning hand screws 30 and 32. The tracing finger 90 is held back during placement of the pattern by turning cap 94 clockwise. This holds and locks the tracing finger 90 away from the pattern 87. This also positions the centres 58 and 60 a sufficient height above the cutting saw 50 to permit the insertion of a raw wood piece 71. After a wood piece has been placed in the adjustable rotatable centres 58 and 60, the centres are locked in place by tightening hand screws 72 and 74. Rotation of the centres is achieved by activating motor 66.

At this point, the saw is turned on and the cap 94 is turned counterclockwise to lower the tracing finger 90 until it tangentially contacts the pattern. With this action, the piece of raw wood 71 held by the revolving centres is lowered in cutting contact with cutting saw 50. Cap 94 is now turned a few additional turns to ensure that the tracing finger 90 will be in continuous contact with the pattern as the tracing finger follows the pattern design. The tracing finger is then moved horizontally along track 16 by turning crank 91. The longitudinal movement moves the finger sideways along the pattern. Where the pattern is high, the finger will move backward, causing the centres to be elevated. The depth and position of the cut is therefore regulated by the forward, backward and sideways movement of the tracing finger. With the above operation, an exact duplication of the wood turning pattern is obtained.

Since certain obvious modifications may be made in the ap-

paratus of this invention without departing from the scope of the invention, it is intended that all matters contained in the foregoing description and shown in the accompanying drawings be interpreted merely as illustrative and that this invention be limited only by the claims which follow.

I claim:

1. A duplicating device for use in combination with a cutting saw comprising:
  - a first support member;
  - a means for mounting said first support member to a cutting saw;
  - a guide means mounted longitudinally across said first support member;
  - a second support member capable of longitudinal and pivotal movement across said first support member, said longitudinal movement being directed by said guide means;
  - a tracing means mounted rearwardly on said second support member for copying a pattern design by a combination of horizontal and pivotal movements;
  - a means mounted to said first support member for holding a pattern design in a longitudinal position for copying by said tracing means;
  - a rotatable means mounted forwardly on said second support for holding a workpiece in proximate cutting relation with a cutting saw when said first support member has been mounted to a table of a cutting saw;
  - a means for transmitting the tracing action of said tracing means to said rotatable means causing said material to be cut by said cutting member in direct response to the horizontal and pivotal movement of said tracing means and to thereby duplicate the design of said pattern.
2. The device of claim 1 wherein said guide means is a track and wherein said second support member includes wheels for horizontal and pivotal movement on said track.
3. The device of claim 2 wherein said means for holding a pattern design comprises a pair of spindled members extending from said first support member.
4. The device of claim 3, wherein said tracing means includes a vertical member and a base member pivotally joined at their ends, said vertical member having a finger extending upwardly and rearwardly therefrom for contacting and tracing said pattern design.
5. The device of claim 4, wherein said tracing means includes a stop means mounted to the rear portion of said base member for limiting the forward pivotal movement of said second support member.
6. The device of claim 5, wherein said first support member includes a pair of vertically spaced, horizontal parallel bars and said stop means comprises a roller journaled in the rear portion of said base member, said roller being positioned loosely between said parallel bars.
7. The device of claim 6, wherein said tracing means includes an adjustable means pivotally mounted at one end to said vertical member for positioning said finger extending from said pivotal forward member.
8. The device of claim 7, wherein the rear portion of said adjustable means is pivotally mounted to an upright extending upward from said base member.
9. The device of claim 8, wherein said rotatable means comprises a pair of longitudinally adjustable spindled members extending from said second support wherein one of said spindled members has a belt pulley for receiving rotation from a power means.
10. The device of claim 9, wherein said device is designed specifically for duplicating wood turnings and includes a means mounted to said first support member for remotely moving said tracing means horizontally along said guide means.
